UNITED STATES PATENT OFFICE.

ROBERT M. APPLETON, OF LAKE VILLAGE, NEW HAMPSHIRE.

DESIGN FOR A STOCKING.

SPECIFICATION forming part of Design No. 15,136, dated July 15, 1884.

Application filed February 27, 1884. Term of patent 14 years.

To all whom it may concern:

Be it known that I, ROBERT M. APPLETON, of Lake Village, Belknap county, State of New Hampshire, have invented a new and original 5 Design for Stockings, of which the following is a full, clear, and exact description, reference being had to the accompanying drawing, making part of this specification.

The design for stockings consists of the circular leg portion A, the tapering ankle part A', and the foot portion B, the leg part being ornamented at the calf with a series of raised circumferential ribs and a series of intermediate stripes, b, the ribs and stripes alternating. The raised ribs and intermediate stripes 10 impart a wavy appearance to the leg of the stocking.

I am aware that knit fabrics—such as hand-knit and machine-made stockings—provided 15 with longitudinal ribs, and called by the trade “ribbed work” or “ribbed stockings,” have

been used heretofore, and I do not claim this feature. By arranging the ribs in horizontal or transverse direction across the knit circular fabric an entirely different effect and 25 a wave-like appearance is imparted to the fabric.

Having thus described my invention, I claim as new and desire to secure by Letters Patent—

The design for stockings herein described, 30 consisting of the foot part, the tapered ankle part, and the circular leg part, the latter being provided at the calf with a series of raised circumferential ribs with intermediate alternating plain surfaces or stripes. 35

In testimony that I claim the foregoing as my invention I have signed it this 7th day of January, 1884.

ROBERT M. APPLETON.
